UNITED STATES PATENT OFFICE.

PETER PRICE, OF HERNDON, WEST VIRGINIA.

JOURNAL BOX.

Application filed June 13, 1922. Serial No. 568,013.

To all whom it may concern:

Be it known that I, PETER PRICE, citizen of the United States, residing at Herndon, in the county of Wyoming and State of 5 West Virginia, have invented certain new and useful Improvements in Journal Boxes, of which the following is a specification.

This invention relates to an improved journal box for railway rolling stock and 10 seeks, as one of its principal objects, to provide a journal box wherein the crown brass employed will be so formed that prolonged wear of the brass will be realized.

A further object of the invention is to provide 15 a journal box wherein the brass may be readily removed at the outer end of the box body.

Another object of the invention is to provide 20 a journal box having a removable door and wherein the door will normally be locked closed.

And the invention has as a still further object, in this connection, to provide a journal box wherein possibility of accidental 25 loss of the door will be reduced to a minimum.

Other and incidental objects will appear hereinafter.

In the drawings:

30 Figure 1 is a perspective view of my improved journal box showing the door removed,

Figure 2 is a sectional view on the line 2—2 of Figure 3, looking in the direction 35 of the arrows,

Figure 3 is a longitudinal sectional view through the journal box, and

Figure 4 is a horizontal sectional view on the line 4—4 of Figure 3, looking in the direction 40 of the arrows.

In carrying the invention into effect, I employ a box body 10 provided in its inner end wall with elongated openings 11 to accommodate a car axle, conventionally shown at 45 12, the axle journal being indicated at 13. Also, the inner end wall of the box body is recessed in the usual manner to receive a dust guard 14. At its outer end, the box body is provided with a door opening 15 and 50 formed on the side walls of the box body to extend horizontally therein, is a pair of oppositely disposed flanges or shoulders 16 reinforced at points midway between their ends by vertical bracing ribs 17. Above the 55 flanges 16, the side walls of the box body are thickened and are thus formed with

sloping inner faces 18 converging upwardly to the top wall of the box body to define a crown brass cavity and mounted in said cavity is a crown brass 19 resting upon the 60 flanges 16. This crown brass is shaped to fit the cavity, being provided with beveled side faces to confront the sloping faces 18 of the cavity so that said faces will coact for sustaining a portion of the load upon the 65 brass. At its upper side, the brass seats flat against the top wall of the box body while at its lower side the brass is recessed medially to fit the journal 13 of the axle 12. As will be observed, the crown brass is, 70 comparatively speaking, wider and thicker than conventional brasses as now in common use and unlike ordinary brasses, is not cut away or channeled at its upper side, so that the brass will, accordingly, give corresponding 75 increased service. By dropping the axle 12, the brass may be shifted outwardly and removed from the box body through the door opening 15 so that the brass may thus be readily renewed at any time. 80

Upstanding from the top wall of the box body near its outer end, is a lug 20, at opposite sides of which are provided openings 21 through said wall, and formed on the side walls of the box body at opposite sides of the door opening 15 are retaining flanges 22, tilted rearwardly toward their upper ends. As particularly brought out in Figure 4, these flanges are undercut and also converge toward their lower ends. Normally 90 closing the door opening 15 is a door 23 adapted to overlie the door opening seating flat against the box body. This door is provided with beveled side edges to engage beneath the flanges 22 and is tapered 95 toward its lower end to wedge between said flanges. At its upper end, the door is formed with an overhanging reinforcing rib 24 and extending rearwardly from the upper end of the door are spaced ears 25 100 straddling the lug 20 of the box body. Depending from said ears are triangular shaped lugs 26 extending through the openings 21 in the top wall of the box body and removably fitting through the ears 25 105 and through the lug 20 is a cotter pin 27 locking the door against opening movement. Thus, this pin will serve to secure the door wedged between the flanges 22 tightly held by said flanges against the box body closing the door opening 15. However, by removing the cotter pin, the door may be 110

readily displaced to permit removal of the crown brass or for the introduction of oil into the journal box. Furthermore, attention is directed to the fact that should the 5 cotter pin become accidentally displaced, the door will, nevertheless, gravitate to wedge between the door retaining flanges for preventing, under ordinary circumstances, the accidental loss of the door. As shown in 10 Figure 2, the lugs 26 depend in front of the crown brass to coact therewith for limiting the brass against outward movement within the box body while said lugs will also coact with the brass for holding the box 15 body against inward movement with respect to the axle so that the box body will thus be prevented from coming in contact with the hub of the adjacent wheel upon the axle.

Having thus described the invention, 20 what is claimed as new is:

1. A journal box including a box body having a lug rising from the top wall thereof, a door closing the box body and provided with spaced ears straddling said lug, 25 and means extending through the ears and said lug locking the door against upward displacement.

2. A journal box including a box body

having a lug rising from the top wall thereof, said wall being formed with openings 30 at opposite sides of said lug, and a door closing the box body and provided with ears straddling said lug, the ears being formed with lugs engaging in said openings, and means extending through the first lug and 35 said ears securing the door against upward displacement.

3. A journal box including a box body, a crown brass therein, a door normally closing the box body and provided with means 40 extending through a wall of the box body locking the crown brass against endwise movement, and means engaging said first mentioned means locking the door against upward displacement.

4. A journal box including a box body, a crown brass therein, a door normally closing the box body and provided with an ear overhanging the box body, a lug on said ear projecting through a wall of the box body 50 locking the crown brass against endwise movement, and means extending through said ear locking the door against upward displacement.

In testimony whereof I affix my signature.

PETER PRICE. [L.S.]
